UNITED STATES PATENT OFFICE.

FRANK R. STEVEN, OF BROOKLYN, NEW YORK, ASSIGNOR TO M. H. TREADWELL COMPANY, A CORPORATION OF NEW YORK.

DUMPING CAR.

Application filed May 18, 1921. Serial No. 470,666.

To all whom it may concern:

Be it known that I, FRANK R. STEVEN, a citizen of the United States, and resident of Brooklyn, in the county of Kings and 5 State of New York, have invented certain new and useful Improvements in Dumping Cars, of which the following is a specification.

This invention relates to dumping cars, 10 and more particularly to slag or cinder cars of the type shown in Patent No. 1,080,619 to Astrom, December 9, 1913, wherein the car body or ladle is so mounted as to be moved transversely of the tracks and simultaneously tilted to discharge its contents.

The aforesaid operation is accomplished by means of a piston and cylinder combination, the full stroke of the piston being utilized to effect the movement of the car body from its central upright position to 20 its outward dumping position upon either side. Hitherto the problem has been to maintain the width necessary for the tilting means within the limitations imposed by 25 the narrow gauge tracks in a crowded plant. The cylinder being disposed transversely, it becomes necessary to shorten the actual stroke of the piston, and to obtain an increased effective stroke by means of an intermediate mechanism. The side upon which 30 the contents of the ladle are to be dumped, whether right or left, is determined by a reversing device. In view of the large masses dealt with, and the forces involved 35 by a shifting center of gravity, checking means, usually in the form of an oil cylinder, are necessary; and I find it also desirable to cushion the various parts against the momentum of the heavy ladle. The demands of safety require a positive locking 40 means for the ladle in either upright or dumping position.

The object of the invention is to combine the actuating, reversing, checking, 45 cushioning and locking means together with a means for increasing the effective piston stroke, in a simple compact structure, employing the least possible number of parts, and all within the aforementioned 50 allowable width and without lengthening the car or increasing the overhang, always undesirable in view of sharp turns and crowded conditions.

With these and other objects in view, I 55 have devised the apparatus embodying my

invention described in the following specification and illustrated in the accompanying drawings, wherein—

Figure 1 is an end elevation of the apparatus; 60

Figure 2 is a plan view of the parts shown in Figure 1; and

Figure 3 is a section taken on the line 3—3 of Figure 2.

1 represents the car body or ladle carried in a yoke or bail 2 supported at either end by a trunnion 3. 4 represents a platform pivotally mounted upon an ordinary wheeled truck (not shown) at either end of the dumping car. Upon platform 4 is 65 mounted a transverse track 5, upon which rolls trunnion 3 in tilting and dumping the car. To insure a positive tilting of car body 1 as trunnion 3 moves along track 5, a stationary rack 6 is mounted on platform 75 4 adjacent and parallel to track 5, and keyed to trunnion 3 is a gear 7 meshing with rack 6.

The dumping mechanism is operated by a power cylinder 8 transversely mounted 80 upon platform 4, steam or compressed air being admitted to either end of cylinder 8 at will through pipes 9 and 10, respectively, by means of a valve 11 connected with the supply pipe 12. Valve 11 also controls the 85 exhaust, it being understood that when fluid is admitted at one end of cylinder 8, the other end is open to the exhaust. Piston 13 within cylinder 8 actuates piston rod 14, which passes through checking cylinder 15 90 containing oil and having a bypass 16 connecting either end. Checking piston 17 is secured to piston rod 14 within cylinder 15. Upon the free end of piston rod 14, that is, the end opposite that attached to piston 13, 95 and beyond checking cylinder 15, is secured a trunnion or cross-head 19, pivotally attached to the respective ends of which, and disposed upon either side of checking cylinder 15 are a pair of parallel links 20 and 100 21. The opposite ends of links 20 and 21 respectively are pivotally connected to a pair of rocker arms 22 and 23, keyed upon rock shaft 24. Keyed upon shaft 24 is a crank arm 25, upon which is pivoted a link 105 26 secured by a strap 27 to trunnion 3, the latter rotating in strap 27 as the same reciprocates.

The locking mechanism comprises a pair of latches 28 and 29, pivotally mounted re- 110

spectively in brackets 30 and 31 secured upon platform 4, the said latches 28 and 29 respectively cooperating with hooks 41 and 42 secured to or integral with, and disposed upon opposite sides of crank arm 25 to lock the latter in either of its limiting positions. Latches 28 and 29, being pivoted to swing freely, normally hang in locking position and are respectively provided with handles 32 and 33 to permit their being drawn back to release the hook 41 or 42 respectively; handle 33 being less accessible is provided with an operating rod 34. Each of latches 28 and 29 is provided with an inclined face 35, whereby as hook 41 or 42 descends it will push the latch aside until locking position is reached, whereupon the latch will swing by gravity to normal position and lock the hook. Beneath each of latches 28 and 29 is a plunger cylinder 36, in which a plunger 37, supported by a spring 38, cushions the hook 41 or 42 as the case may be, and constitutes a resilient stopping device for determining the limiting positions of crank arm 25 and of ladle body 1. Plungers 37 also by exerting continual pressure upon the under sides of hooks 41 and 42 respectively when the same are locked, hold the same firmly in engagement with their respective latches and prevent any possibility of accidental release. The hooks may be easily disengaged from the latches by admitting pressure upon the proper side of the piston 13 to compress spring 38; then the release having been effected pressure is admitted upon the opposite side to advance the piston and move the ladle 1.

A simple reversing device is provided in the form of an alternative connection between crank arm 25 and link 26. As shown, the ladle 1 is in central and upright position, and piston 13 is at the left hand end of its stroke. Crank arm 25 is secured to link 26 by a removable pivot pin passing through hole 39 in link 26. As the piston 13 moves to the right, car body 1 will dump to the right. When it is desired to dump to the left, crank arm 25 is disengaged from link 26 while the ladle 1 is in upright position, by the removal of the pivot pin from hole 39. Piston 13 is now moved to the right hand end of its stroke, and crank arm 25 is re-engaged in its new position with link 26 by the insertion of the pivot pin in hole 40, provided in link 26 for that purpose. Now when piston 13 is moved to the left, ladle 1 will dump to the left.

The advantage of compactness of structure afforded by the invention is evident. In the conversion of reciprocating motion into rotation, an intermediate element, one end of which reciprocates and the other end rotates, such as in the ordinary connecting rod, is always necessary; and this intermediate element must be relatively long as compared

with the stroke of the piston. In the apparatus described, the intermediate element comprises the links 20 and 21, and by spacing these relatively long members on either side of checking cylinder 15, a substantial reduction in the over all width of the mechanism is effected. Moreover, by passing piston rod 14 through both ends of cylinder 15, the checking upon either side of piston 17 will be the same, thus avoiding the differential effect due to the area of the piston rod. Furthermore, crank arm 25 is made relatively long as compared with rocker arms 22 and 23, thereby greatly increasing the effective piston stroke, and to a corresponding extent reducing the actual travel of piston 13. The advantage here gained is cumulative; not only are the lengths of both cylinders 8 and 15 reduced, but links 20 and 21 may be shortened to an extent far greater than the saving in the length of the piston stroke itself. Crank arm 25 not only thus constitutes a part of the stroke multiplying device, but, with hooks 41 and 42, preferably integral therewith, also affords a simple and convenient means of locking and of cushioning, in conjunction with latches 28 and 29 and with plungers 36 respectively; and together with link 26 and holes 39 and 40 it affords a convenient reversing means. The result of thus combining the various functions in the aforesaid elements, and of so arranging these elements, is to reduce to a minimum the necessary number of separate parts, and to maintain the structure within the desirable limits of length and breadth. In the following claims the combination of rocker arms 22 and 23, shaft 24 and crank arm 25 is referred to as an "actuating member," while crank arm 25 alone is referred to as an "actuating arm."

What I claim is:

1. The combination in a dumping car, with a frame and a tilting and movable car body, of a power cylinder and piston, a trunnion supporting the car body and supported on the frame, an actuating arm supported on the frame, connecting means between the arm and the trunnion, a link pivoted upon the movable element of said cylinder and piston, and connecting means between said link and said arm.

2. The combination in a dumping car with a frame and a tilting and movable car body, of a trunnion supporting the car body and supported on the frame, an actuating arm, means operating through said arm for tilting said car body, and means carried by said arm and by said frame for locking the car body in predetermined position.

3. The combination in a dumping car with a frame and a tilting and movable car body, of a trunnion supporting the car body and supported on the frame, an actuating

- arm, means operating through said arm for tilting said car body, a latch mounted on said frame, and means integral with said arm for engaging said latch when the arm reaches limiting position.
4. The combination in a dumping car with a frame and a tilting and movable car body, of a trunnion supporting the car body and supported on the frame, an actuating arm, means operating through said arm for tilting said car body, a pair of latches mounted on said frame, and means carried by said arm for engaging said latches respectively when the arm reaches its limiting position.
5. The combination in a dumping car, with a frame and a tilting and movable car body, of a power cylinder and piston, a trunnion supporting the car body and supported on the frame, an actuating arm supported on the frame, connecting means between the arm and the trunnion, connecting means between the arm and the movable element of said cylinder and piston, a latch secured to said frame, and means carried by said actuating arm cooperating with said latch to lock the car body in predetermined position.
6. The combination in a dumping car with a frame and a tilting and movable car body, of a trunnion supporting the car body and supported on the frame, an actuating arm, means operating through said arm for tilting said car body, and means carried by said frame for resiliently engaging said arm as the latter approaches limiting position.
7. The combination in a dumping car with a frame and a tilting and movable car body, of a power cylinder and piston, a trunnion supporting the car body and supported on the frame, an actuating arm pivoted to the car frame, a link connecting said arm with the movable element of said cylinder and piston, and means adapted to connect the trunnion when in central position with the arm when the same is in either of its limiting positions.
8. The combination in a dumping car with a frame and a tilting and movable car body, of a power cylinder and piston, a trunnion supporting the car body and supported on the frame, an actuating arm, connecting means between the arm and the movable element of said cylinder and piston, means adapted to connect the trunnion when in central position with the arm when the same is in either of its limiting positions, and means carried by the arm and by the frame for locking the car body in predetermined position.
9. The combination in a dumping car with a frame and a tilting and movable car body, of a power cylinder and piston, a trunnion supporting the car body and supported on the frame, an actuating arm supported on
- the frame, connecting means between the actuating arm and the movable element of said cylinder and piston, means adapted to connect the trunnion when in central position with the arm when the same is in either of its limiting positions, a pair of latches carried by said frame, and means carried by said arm cooperating with said latches to lock the car body in predetermined position.
10. The combination with a pivotal dumping car body, of a car frame on which the same is mounted, trunnions on which the dumping body is mounted, said trunnions being movable across said car frame in dumping, a fluid pressure cylinder and piston mounted on an end portion of the frame, a crosshead connected with said cylinder and piston and disposed on one side of the dumping body trunnions when in normal or upright position, an actuating arm for moving the trunnions, said arm being located on the opposite side of the normal position of the trunnions from said crosshead, and connecting means between the actuating arm and crosshead.
11. The combination in a dumping car with a tilting and laterally movable car body, of a car frame, a trunnion supporting said car body and supported on said car frame, a power cylinder mounted upon said frame, a piston working in said cylinder, actuating means between said piston and said trunnion for laterally moving and tilting said car body, means in said actuating means for multiplying the effective stroke of said piston, and a resilient stop for limiting the position of said car body.
12. The combination in a dumping car with a tilting car body, of a trunnion supporting said car body and supported on said frame, an actuating member pivotally mounted in the frame, means for applying a thrust upon said actuating member to rock the same, means connecting said actuating member to said trunnion to tilt the car body, said connecting means being attached to said actuating member at a greater distance from the center of rotation of the latter than the point of application of said thrust, and resilient stop means limiting the movement of said actuating member.
13. The combination in a dumping car with a tilting car body, of a trunnion supporting said car body and supported on said frame, a cylinder mounted on said frame, a source of fluid pressure to said cylinder, controlling means for said fluid pressure, a piston working within said cylinder, a piston rod actuated by said piston, a checking cylinder containing checking fluid, a piston in said checking cylinder, said piston rod passing through said checking cylinder and secured to last mentioned piston, a pair of links disposed on either side of said checking cylinder and each pivotally connected at one end

to the free end of said piston rod, and connecting means between the opposite ends of said links and said trunnion for tilting said car body.

5 14. A dumping car body provided with a trunnion transversely movable in dumping, a fluid pressure cylinder and piston located to one side of the normal position of said trunnion, a pivotal actuating arm adjacent 10 the cylinder and piston, connecting means

between the arm and cylinder and piston, a link connecting said arm with the trunnion, and means for varying the effective length of said link according to the direction of movement of the car body in dumping. 15

Signed at New York, in the county of New York and State of New York, this 16th day of May, A. D. 1921.

FRANK R. STEVEN.
